UNITED STATES PATENT OFFICE.

EARLE A. BERRY, OF KANSAS CITY, MISSOURI.

SILO-LADDER.

1,162,743.

Specification of Letters Patent.

Patented Dec. 7, 1915.

Application filed May 3, 1915. Serial No. 25,448.

To all whom it may concern:

Be it known that I, EARLE A. BERRY, a citizen of the United States, residing at Kansas City, in the county of Jackson and State of Missouri, have invented certain new and useful Improvements in Silo-Ladders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to silos, and more particularly to a silo of the stave type wherein vertically arranged staves are held in proper relation to maintain the contour of the silo by circumferentially arranged bands or hoops; the principal object of the present invention being to provide an improved ladder for reaching the upper portion of the silo to adjust the supply tube or to reach any vertical point of the silo to facilitate the adjustment of the hoops. In accomplishing this object I have provided improved details of structure, the preferred forms of which are illustrated in the accompanying drawings, wherein:—

Figure I is a perspective view of a silo equipped with a ladder comprising my improvements. Fig. II is an enlarged detail perspective of part of the silo, showing the hoop and the application of a ladder section thereto.

Referring more in detail to the parts:—

1 designates a silo of any ordinary stave construction, and having hoops 2 that are held together by the adjusting devices 3, 40 which may comprise turnbuckles or the like; the body of the silo being topped by a roof 4 having the usual dormer window 5 through which the end of the filling tube may be projected.

Attached to the hoops 2, or to as many of them as may be necessary, are ladder sections 6, each of which comprises upper legs 7 having hooked ends 8 that may be turned under the hoops 2 and are of sufficient length 50 to space the body portion 9 away from the silo a suitable distance for providing foot room between the rungs 10 and the silo; the lower portion of the section being equipped with legs 11 having flanges 12 that lie 55 against the silo and are provided with apertures 13 through which the screws 14 may

be projected to securely attach the ladder section in place. The ladder section is preferably of skeleton construction and formed of suitable cast metal; the stepped part comprising the rungs 10 and side standards 15 for spacing the rungs; and the upper legs 7 being preferably flattened at their ends in order that they may be slipped easily between the staves and hoops. As the hoops 60 are, in ordinary use, placed a specified distance apart in the silo, the ladder sections may be made of such length that the upper rungs 10 are located in substantial horizontal alinement with the hoops to which 65 the sections are attached, and the lower rungs 10 placed midway between the hoops, in this way providing steps of equal length 70 between the rungs on the same sections and on adjoining sections.

With a ladder of this construction the independent sections may be applied to the hoops while the silo is under construction, or they may be applied to previously erected silos, as the hooks may be forced between the 80 hoops and the staves when the ladder sections are tipped at a right angle to their ultimate position and then swung down until the lower legs rest against the staves.

It is apparent that with the sections constructed as disclosed, the weight of a person climbing the ladder is placed on the staves as well as on the hoops, and that the sections not only fail to drag materially on the hoops but actually serve to maintain the hoops in 90 place owing to the anchorage of the lower portions of the ladder sections.

A silo may be equipped with a ladder of this construction at any point about the circumference of the structure, so that if a silo 95 is arranged close to a barn or other building, with the opening facing and closely adjacent the building, the ladder may be arranged on the opposite side so that easy access may be had to the filling window or to 100 the hoops, when it is necessary to adjust the latter.

Having thus described my invention, what I claim as new therein and desire to secure by Letters-Patent, is:—

1. The combination with a body having encircling hoops, of a ladder section comprising a rung portion and legs extending inwardly from the rung portion and having upturned hooks at their inner ends adapted 110 to extend between a hoop and the elements of the body, with the ends of the hooks over-

lying the hoop, the rung portion having spacing legs at its lower end engaging the face of the structure below the hoop, and means for securing the lower legs to the structure.

2. The combination with a structure having one or more encircling hoops, of a ladder section having inturned legs at its upper and lower ends, the ladder section consisting of two rungs, and spacing members, the top rung having inturned legs, the said

legs having upturned hooks at their inner ends adapted to engage the hoops and partly encircle the same; the spacing members being integral with the rungs; the lower rung having inturned legs and the said legs bearing against the structure and having means for attachment to the structure.

In testimony whereof I affix my signature.

EARLE A. BERRY.
